[57] **CLAIM**

The ornamental design for an antenna mounting device, substantially as shown.

DESCRIPTION

FIG. 1 is a front elevational view of an antenna mounting device, showing my new design;
FIG. 2 is a side elevational view of my said device;
FIG. 3 is a top end view thereof;
FIG. 4 is a cross-sectional view of the device of FIG. 1, taken along the line 4—4 thereof; and
FIG. 5 is a cross-sectional view of the device of FIG. 1 taken along the line 5—5 thereof.

FIG. 4

FIG. 3

FIG. 5

FIG. 1

FIG. 2
